ELECTRIC SWITCH OF THE TOGGLE TYPE

Laddie A. Sanda, Newton, Mass., assignor to
Ark-Les Switch Corporation, Watertown, Mass.,
a corporation of Massachusetts

Application August 23, 1950, Serial No. 180,962

1 Claim. (Cl. 200—16)

1 This invention relates to an electric switch having a projecting handle to be rocked back and forth to operate the switch, switches of this kind being known as toggle switches. An object of the present invention is to provide a switch composed of parts which are easy and cheap to manufacture and which can quickly be assembled and secured together without the use of rivets, screws or other similar fastening elements.

Other advantageous features of construction will be evident from the following description of the invention and from the drawing, of which—

Figure 1 is an end elevation of a switch embodying the invention;

Figure 2 is a section on the line 2—2 of Figure 1, on a larger scale;

Figure 3 is a section on the line 3—3 of Figure 1, on a larger scale;

Figure 4 is a section on the line 4—4 of Figure 3;

Figure 5 is a section on the line 5—5 of Figure 2;

Figure 6 is a perspective view of a partition element in the switch;

Figure 7 is a perspective view of a top plate for the switch;

Figure 8 is a perspective view of one of the side contact elements;

Figure 9 is a perspective view of a modified form of side contact element;

Figure 10 is a perspective view of one of the bridging conductors;

Figure 11 is a perspective view of the insulation box, a portion being broken away; and

Figure 12 is a perspective view of the box inverted.

The switch illustrated on the drawing comprises a rectangular box 20 which may conveniently be made of molded plastic material of a type which is electrical insulation. As indicated in Figure 11, this box is provided with a pair of guide fins 22 and 24 which project toward each other from the end walls of the box and are preferably in alignment. The lower portion of the box is provided with a longitudinal partition wall 26 and transverse partition walls 28 and 30, these walls defining six compartments in the lower part of the box to accommodate suitable terminals for the switch at one end of the box. Two contact elements 32 and 34 are mounted against the inner face of the wall. In like manner two similar contact elements 36 and 38 are mounted against the inner face of the wall at the other end. The contacts 32 and 34 are separated and insulated from each other by the fin 22. The

2 contacts 36 and 38 are similarly separated and insulated from each other by the fin 24. A pair of contact elements 40 and 42 are mounted in the side walls of the box so as to face each other from the midportions of the respective side walls. Each of these elements has a lower portion 44 and an upper portion 46. The upper portion is in the form of an obtuse dihedral angle or V which projects from the inner face of the side wall into the interior of the box.

A carrier 50 is slidably mounted in the box, this carrier preferably being a rectangular block of insulation having slots 52 and 54 extending into the ends thereof to receive respectively the fins 22 and 24 by which the carrier is guided as it is moved back and forth within the box. The sides of the carrier 50 are preferably concaved or otherwise cut away as indicated in Figure 2. Two bridging conductors 56 and 58 are supported by the carrier, each bridging conductor consisting of a strip of resilient metal such as brass extending lengthwise of the block and having its terminal portions bent around to bear against the end faces of the block. These terminal portions of the strips 56 and 58 have contact elements 59, 60, 61, and 62 opposed to respective fixed contact elements 32, 34, 36, and 38. Hence when the block is moved to the right as in Figure 2, the elements 60 and 62 move into contact with the fixed elements 36 and 38 respectively. When the carrier is moved to the left, the elements 59 and 61 engage the fixed elements 32 and 34 respectively. The bridging conductors 56 and 58 are bent at their midportion to form V projections or obtuse dihedral angles 63 and 64 facing outwardly and engaging one or the other flanks of the dihedral angles which form a part of the corresponding terminals. The side faces of the carrier 50 are made concave as indicated in Figure 2 to provide clearance when the midportions of the bridging conductors are sprung inward. The angular magnitude of the dihedral projections 40 and 42 is equal to that of the dihedral projections 63 and 64 and these projections are so related to each other as to maintain contact between the bridging conductors and the fixed side elements for all positions of the carrier. When the carrier is moved from its central position, such movement is aided by the camming effect of the sloping faces of the resilient strips 56 and 58 against the sloping faces of the fixed contact elements 40 and 42 to press the carrier to one end or the other of its stroke in the box. When it is at the end of its stroke, the bridging conductors engage the two fixed contact ele-

ments at the corresponding end of the box. Each of the dihedral portions of the fixed terminals 40 and 42 may have a slot 65 at its apex, as shown in Figures 2 and 9. When the carrier is at the midpoint of its stroke in the box, the apex of each dihedral projection 63 and 64 enters the slot or notch 65 in the corresponding fixed element 40 or 42 and holds the carrier in its mid position. Thus the switch has three possible positions in which the side contact elements may be electrically connected to the fixed contact elements at one end of the switch, to those at the other end or to neither.

The box and assembled parts are carefully designed so as to provide effective insulation between the several charged parts. For this purpose the carrier 50 itself is of insulating material and has end slots 52 and 54 by which it telescopes with the fins 22 and 24 to provide a horizontal barrier of insulating material between the charged elements of the switch on one side of the median plane and those on the other. Underlying the carrier 50 is a floor plate 66 having end slots 67 to accommodate the fins 22 and 24 and having side notches 68 to accommodate the dihedral projections of the fixed side elements. This floor plate rests on the top edges of the partition members 26, 28, and 30 and thus effectively insulates the bridging conductors and their cooperating terminals from the terminal portions of the various conductors which are disposed within the lower compartments in the box. A top plate 69 of insulating material is preferably employed on the top of the box, this plate resting on the upper edges of the shell of the box and the upper edges of the fins 22 and 24 which project in from the ends of the box. This plate has a central aperture or slot 70. Overlying the top plate 69 is a sheet metal cover plate 70 which is provided at its corners with tongues 72 adapted to be bent to catch under suitable shoulders 74 which may be formed on the outside of the box wall. On the cover plate 70 a socket member 80 is centrally mounted, this socket member being preferably externally screw threaded so that a nut may be threaded thereon to assist in securing the switch in place for use. As shown in Figure 3, the socket member 80 has a cylindrical bore which tapers slightly at its upper end. Within the socket bore is fitted a ball 82, the two elements forming a ball-and-socket joint. A lever 84 projects up from the ball 82 to be grasped for the operation of the switch. Projecting down from the ball 82 and through the aperture 76 is a stem 86 having a rounded tip 88 engaging in a central recess 90 in the carrier 50. A suitably shaped rubber ring or washer 92 is mounted in the socket 80 below the ball 82 to maintain the ball in its proper position within the socket the ring 92 has an approximately triangular cross-section forming an upper cavity to fit against the ball 82 and a frusto-conical lower cavity to permit rocking movement of the ball and handle assembly. Such rocking movement results in arcuate movements of the tip 88 toward one or

the other end of the box so as to move the contact elements of the bridging conductors at the leading end of the carrier into direct contact with the opposing fixed contact elements in the box.

5 The current is preferably introduced into the switch through the side contact elements 40 and 42 which are always in contact with the bridging conductors 56 and 58 respectively. Movement of the carrier to one end or the other of the box thus connects the side elements to one of the pairs of fixed elements at the ends of the box. The side contact elements 40 and 42 thus have the double function of being current carrying contact members and acting mechanically to press the carrier toward one or the other of its extreme positions.

10 Figure 8 shows a modified form of side contact element in which the dihedral member has no slot 65. When contact elements of this kind are mounted in the box 20, there is no stable neutral position for the carrier 50. In other words, the carrier must occupy one or the other of its extreme positions when left to itself.

15 I claim:

20 25 An electric switch comprising a rectangular box of insulation having therein two aligned fins of insulation projecting toward each other from opposite ends of the box, four metal switch elements mounted within the box against the surface portions of said ends on both sides of said fins, a carrier of insulation slidably longitudinally within said box, said carrier having a slot in each end into which project said fins respectively, a pair of bridging conductors carried by said carrier, each said bridging conductor consisting of a strip of metal extending along a side of the carrier with extremities bent to bear against the ends of the carrier and to be moved by the carrier into selective contact with the opposing switch elements at the ends of the box, each said conductor having a midportion bent to form an outwardly projecting V, a metal switch element mounted in each side wall of the box opposite one of said conductors and including an inwardly directed V portion in engagement with the V of the corresponding conductor, a cover on the box, and an operating lever workably mounted on the cover and engaging the carrier to shift the carrier longitudinally in the box when the lever is rocked.
